UNITED STATES PATENT OFFICE

2,226,483

BOTTLE CAPPING MACHINE

Lynn L. Seymour, De Kalb, Ill., assignor to The Creamery Package Mfg. Company, Chicago, Ill., a corporation of Illinois

Application June 23, 1939, Serial No. 280,750

17 Claims. (Cl. 226—81)

This invention relates to bottle capping machines, and more especially it relates to improvements in bottle capping machinery of the type that applies flexible caps to milk bottles and similar receptacles or containers.

More particularly the machine is designed for use in applying caps of the type that constitute the subject matter of U. S. Patent No. 2,157,601, issued May 9, 1939, to John R. Gammeter, which caps are made of two plies of thin, stretchable sheet material, for example, the rubber hydrohalide film marketed under the trade name "Pliofilm." The invention is an improvement upon the bottle capping apparatus of my prior U. S. Patent No. 2,164,026, issued June 27, 1939, the improvement residing primarily in the fingers that engage the caps to stretch them over the bead at the top of bottles, and in mechanism for operating said fingers, and for swinging the nozzle members into and out of axial alignment with the magazines that hold the caps.

The chief objects of the invention are to provide a simplified construction that may be more readily manufactured than the prior construction, whereby economy of time, labor, and cost is effected. Other objects will be manifest as the description proceeds.

Of the accompanying drawings:

Figure 1 is a plan view of the bottle capping machine taken just below the bottle cap magazines and the nozzle members;

Figure 2 is a plan view, on a larger scale, taken on the line 2—2 of Fig. 3, showing the bottle cap magazines;

Figure 3 is a section on the line 3—3 of Fig. 2, showing one phase of a bottle-capping operation;

Figure 4 is a section on the line 4—4 of Fig. 2;

Figure 5 is a section on the line 5—5 of Fig. 2;

Figure 6 is a section on the line 6—6 of Fig. 3;

Figure 7 is a vertical sectional view through the upper part of the machine showing the final phase of a bottle capping operation;

Figure 8 is a plan view of one of the caps; and

Figure 9 is a diametric section through one of the caps.

Referring now to Fig. 1 of the drawings, there is shown the top of a closed housing 10, which housing is suitably supported by a plurality of spaced legs 11. Within the housing 10 are operating mechanisms (not shown) including a motor, which mechanisms are identical with similar mechanisms shown in my prior U. S. patent aforementioned, and to which reference is directed for details thereof. Extending upwardly

from the housing 10 is a vertical shaft 12 that is driven by the power mechanism within the housing. Through suitable gearing the shaft 12 drives a sprocket (not shown) about which is trained an endless chain or link belt 13, said belt having an elongated horizontal reach above the housing 10, and also passing about an idler sprocket (not shown) that is rotatably mounted in spaced brackets 14, 14 depending from one end of spaced angle irons 15 and 16 which in turn are supported upon a suitable bracket carried atop of the housing 10. The angle irons 15, 16 serve to support the upper reach of the conveyor belt 13 whereby bottles may be conveyed to the capping mechanism of the machine. Angle iron 15 extends across the front of the machine and has a cut-away portion 17 that enables the conveyor belt 13 to pass downwardly about its driving sprocket, while angle iron 16 has its horizontal portion cut away as at 18 to enable the conveyor belt to pass downwardly and this iron is bent back to provide an angularly disposed portion 19 for a purpose subsequently to be explained. The lower reach of the belt 13 is supported in any suitable manner, but preferably as shown in my prior patent aforementioned.

Throughout a portion of its length the angle iron 15 is provided with an upstanding outer guard rail 21 supported at one point as at 22 upon a bracket 23. A similar bracket 24 supports the inner end of the guard rail as at 25, but the latter bracket is extended below the angle iron and is formed with a rectangular member 26, additionally supported at 27. Three notches 28, 29 and 30 are formed in member 26. An inner guard rail 31 is arranged on angle iron 16, both rails preferably being curved as at 32 to enable the entrance of bottles onto conveyor belt 13. Guard rail 31 preferably is adjustably secured to member 16 to allow movement toward and from rail 21 whereby the rails can be made to accommodate bottles of different sizes such as quarts, pints and half pints.

Bolted to angle iron 16 is a bracket 35 that carries a vertically arranged hinge pin 36. Pivoted at one end to the latter is a link 37, the other end of which is pivotally connected at 38 to a bracket 39 that is secured to rail 31. In like manner a bracket 40, identical with bracket 35 but spaced from the latter, is secured to angle iron 16 and carries a rotatable pin 41 upon which one end of a link 42 is secured, the other end of link 42 being pivotally connected at 43 to a bracket 44 that is secured to rail 31. The pin 41 projects downwardly from bracket 40,

and mounted upon the projecting end thereof is a lever 45 that extends beneath the angle irons 15, 16 and has its free end portion arranged for insertion alternatively in one of the slots or notches 28, 29 or 30. As shown in Fig. 1, the lever is in slot 28 and the rails are far enough apart to admit quart bottles to the conveyor belt. The action of lever 45 and link 42 is a bell crank action, and movement of said lever sufficient to turn pin 41 will move said link 42. Through the agency of the latter, rail 31 may be moved toward or from rail 21, and since link 37 also is pivoted to rail 31, the movement of link 37 will be similar to that of link 42. Hence if it is desired to use pint bottles, lever 45 is moved to slot 29 which movement brings the rails closer together, and for half pints the lever will be in slot 30, thus moving rail 31 even nearer to rail 21. Reverse movement of lever 45 changes the spacing of the rails accordingly.

As is clearly shown in Fig. 1, a table or platform 48 is arranged with its upper face in substantially the same horizontal plane as the upper surface of the conveyor belt 13. This table 25 is supported across its front by angle iron 15, being secured to the latter by screws 49, 49. At its rear the table 48 is secured by screws 50 upon a horizontal supporting member 51 that extends laterally from a vertical angle iron 52 that is bolted to the side of housing 10. Additional support for the table 48 is provided by the portion 19 of angle iron 16 to which the table is secured by means of screws. Table 48 is of such contour that it will not interfere with the movable 30 parts of the machine, yet will furnish support for the bottles, upon occasion, as when the bottles leave the conveyor belt to be delivered to the capping mechanism, and after the bottles have been capped and are removed from the 35 movable parts of the machine.

Secured to and arranged above table 48 are additional guard or guide rails 54 and 55 which preferably are curved and arranged as shown in Fig. 1. These rails may be joined in a common 45 supporting section 56 which may be secured to the table by suitable securing means 57. Rail 54 also is secured to the table as at 58, and strengthening webs 59 and 60 may be arranged outwardly of the section 56. Between one end of rail 55 and the adjacent end of rail 21, a flexibly mounted rail section 61 is arranged in alignment with the adjoining rails. As shown, rail section 61 has an arm 62 extending therefrom and pivoted to a pin 63 mounted in one end of a bracket 64 50 that is secured to the front margin of table 48. A tension spring 65 has one end connected at 66 to arm 62 and its opposite end secured to a fixed point 67 on the web 59, said spring normally urging rail section 61 toward the conveyor belt, 60 but allowing movement of the section away from the belt against the tension of the spring. Rail section 61 is provided with adjustable stop member 68 that is engageable with angle iron 15 to prevent inward movement of said rail section 65 beyond the plane of alignment with the adjacent rails. The function of the yielding rail section 61 presently will be explained.

The conveyor belt 13 is adapted to convey bottles to a point opposite rail section 61, at 70 which point a bottle feed wheel 70 is arranged to engage each bottle and move it from the conveyor onto another part of the apparatus. Wheel 70 is removably mounted upon the upper end of shaft 12 (Fig. 7) for rotation with said shaft. A pin 71 secured in wheel 70 extends into

a bearing member 72 arranged on top of housing 10 and keyed to shaft 12 as at 73 whereby rotation of bearing member 72 will effect rotation of wheel 70. The periphery of the wheel 70 is formed with two oppositely disposed cut-out or 5 re-entrant portions 74, 74, each of which, as the wheel rotates, engages a bottle on belt 13 and moves it counter-clockwise as viewed in Figs. 1, 2 and 6 for approximately 180°, guard rail 55 being utilized as a guide in the movement of the 10 bottle, while a portion of the table 48 serves as a support for the bottle until it reaches the next part of the apparatus. Wheel 70 is made in various sizes with cut-out portions 74 altered to 15 accommodate bottles of quart, pint, or half pint size, and each wheel 70 carries its own pin 71. Such wheel readily may be changed on the shaft 12 by displacing pin 71 and removing the wheel, placing a different wheel on the shaft and replacing its pin 71. 20

As long as a bottle is in proper position on belt 13 to be engaged by one of the cut-out portions 74, such bottle will be properly moved from the conveyor by the feed wheel. But if a bottle should be out of place so as to be engaged by the 25 periphery of the feed wheel, between the cut-out portions, such bottle will be forced against the yieldingly mounted rail section 61, the latter giving way sufficiently to avoid compressive stress on the bottle. Continued rotation of the feed 30 wheel eventually will bring one of its cut-out portions into registry with the bottle, and spring 65 thereupon will move the rail section 61 back to its normal position and thereby force the bottle into the cut-out portion so that the bottle 35 will thereupon be removed from the conveyor belt in the manner intended.

As is best shown in Fig. 7, a vertical non-rotatable elevating shaft 77 extends from within the housing 10 to a substantial elevation above 40 said housing. The shaft 77 is capable of axial adjustment by mechanism comprising a hand wheel 78, said mechanism being otherwise omitted herefrom but being shown in detail in my prior U. S. patent aforementioned. The arrangement is such that shaft 77 may be manually raised or lowered by the turning of hand wheel 78 to adapt apparatus carried by said shaft to receive quart, pint or half pint bottles. 45

Mounted upon the shaft 77 is a quill or sleeve 50 80 that is movable axially with said shaft and movable angularly relatively thereof. The lower end of sleeve 80 is disposed within the housing 10 and rests upon a thrust collar (not shown) carried by the shaft 77. A worm gear 81 (Fig. 55 7) is suitably mounted for rotation in the housing 10 and has an elongated hub portion 82 extending upwardly therefrom, said hub portion being concentrically disposed with relation to the axis of sleeve 80 and keyed to the latter at 83 60 so as to effect rotation thereof. Since sleeve 80 is raised and lowered with shaft 77, an elongated keyway is utilized in the connection with gear 81 whereby this connection will not be disturbed by movement of the sleeve. Gear 81 has driving engagement with gear means (not shown) by means of which sleeve 80 will be rotated at the same angular speed as shaft 12 and at determinate speed ratio with relation to the drive of the conveyor belt 13. The sleeve 80 rotates in clockwise direction as viewed in Figs. 1 and 6. 65

A bottle rotor 86 is secured to the upper end portion of hub 82 by means of a key 87, said rotor resting upon the upper end of a projection 88 rising from the housing 10. If desired, a thrust 75

bearing may be positioned between the rotor and said projection 88. The rotor 86 is generally circular in plan, and at diametrically opposite points thereof it is formed with respective vertical slide-
 5 ways 89 in each of which is slidably received a post or vertical leg 90 of an individual bottle table 91 positioned upon the upper end thereof, each bottle table 91 being flanged as at 92 to prevent displacement of a bottle thereon. The lower end
 10 portion of each post 90 is provided on its outwardly facing side with a cam roller 93 that engages an arcuate cam track 94 that is mounted upon the top of housing 10, concentrically of shaft 77. The cam 94 as shown has a linear arc
 15 of 245° of which 60° from the roller-receiving end is a sharply upward incline shown at A in Fig. 7, the succeeding 120° being a gradual upward incline to the high point thereof and shown at B in Fig. 7, the remaining 65° being a sharply downward incline indicated at C in Figs. 1, 2 and
 20 6. The cam is so arranged with relation to the other elements of the apparatus that its roller-receiving end, which is the low point of the cam, and the highest point of the cam are located in
 25 the same vertical plane as the shafts 12 and 77. Thus it will be observed that in Fig. 7 the bottle table 91 at the left is in its lowermost position and the bottle table at the right is in its uppermost position. Similarly in Fig. 1 the near table 91 is
 30 in lowermost position and the far table is in uppermost position. Adjustable abutment set screws 95 are mounted upon the top of the rotor 86 beneath the respective bottle tables 91 for supporting the latter in determinate, lowered position when their cam rollers 93 are not in engagement with the cam 94. From the foregoing it will be observed that the time required to lower each bottle table is much less than the time required to elevate the same to its highest point. To
 40 assure that the bottle tables 91 will move downwardly when their cam rollers 93 move onto the downwardly inclined region C of the cam 94, said downwardly inclined region has a guide plate 96 overlying the same in spaced relation thereto, and beneath which the cam rollers travel when moving down the inclined cam portion C, said guide plate being secured to the outer lateral face of the cam structure. Both cam rollers 93 operate in the same manner and thus alternately raise and lower the tables 91 and bottles thereon.
 45 An oil seal 97 may be threaded onto the upper end of hub portion 82 to prevent oil from within the housing 10 from rising along said hub or along the sleeve 80.
 50 Also mounted upon the sleeve 80 is a capper frame 100 that is positioned near the upper end thereof and secured thereto by set screws 101, 101, the arrangement being such that the capper will rotate with said sleeve and also move axially therewith. At diametrically opposite points capper frame 100 is provided with respective tubular heads or bearing structures 102, 102 that are disposed on vertical axes, and disposed below said heads, in spaced relation thereto and concentric with said axes, are respective finger-supporting rings 103, which rings are integral with the capper frame 100 and of somewhat larger diameter than the said heads. Slidably mounted for vertical movement in each head 102 is a tubular sleeve 104, the bore of which is somewhat enlarged or grooved at 105 adjacent the lower end thereof, the lower end of the sleeve being hardened and its lower inner margin rounded as shown at 106 so as to constitute a cam for con-

trolling the operation of cap-engaging fingers as subsequently will be explained.

For effecting vertical movement of the sleeves 104 in timed relation to each other, each of said sleeves is provided at diametrically opposite points thereon with radially outwardly projecting studs 108, which studs extend to the exterior of the head 102 through respective vertical slots 109 in said head that extend downwardly from the upper margin of the latter. As is best shown in Fig. 2, the two slots 109 of each head 102 are disposed in a plane that is transverse to a plane passing through the axis of the capper frame and the axis of the head. Journaled on the end portion of each stud 108, exteriorly of the head 102, is a bearing block 110, which bearing blocks are slidably mounted in respective slots 111 formed in the free ends of the respective arms of a forked lever arm 112. The latter is pivotally mounted upon the capper frame at 113, and constitutes one arm of a bell crank of which an upwardly extending arm 114 is the other part thereof. As is clearly shown in the drawings, the said bell cranks are disposed at diametrically opposite points on the capper frame. The free ends of the bell crank arms 114 carry respective axially extending studs 115, and a cam roller 116 is journaled upon each of said studs, said cam rollers engaging a cam 117 that is fixedly mounted upon the shaft 77 immediately above the upper end of sleeve 80. The upper end of each stud 115 is grooved to receive a yoke 118, and said yokes are connected to each other by a pair of tension springs 119, which springs are disposed on opposite sides of the shaft 77 and serve to hold the cam rollers 116 in engagement with the cam 117.

Since the capper frame 100 is secured to the sleeve 80 and the cam 117 is secured to shaft 77, it follows that rotation of the sleeve in clockwise direction relatively of the shaft 77 will carry the cam rollers 116 around the periphery of said cam and thereby effect operation of the bell cranks to raise or lower the sleeves 104. As is shown in Fig. 2, the cam 117 has a relatively short uniform radius throughout a peripheral region W, which region is 200° in extent, and a diametrically opposite region X of relatively long uniform radius throughout a peripheral region of 40°. Said regions W and X are connected by symmetrically disposed regions Y and Z, each of which is 60° in extent. When a cam roller is on cam surface W, the sleeve 104 is in the elevated position shown at the right in Figs. 3 and 7 and when a cam roller is on the cam surface X the sleeve 104 is in the lowered position shown at the left in said figures. The cam 117 requires to be determinately positioned with relation to the cam 94 previously described, and as shown, the medial point of cam surface X of cam 117 is positioned 45° anterior to the low end of cam surface A of cam 94. The arrangement is such that when the capper frame 100 and bottle rotor 86 are rotating clockwise as viewed in Fig. 2, a cam roller 116 will be moving over cam surface Z and the corresponding sleeve 104 will be rising as a cam roller 93 of the bottle table 91 directly below said sleeve moves onto the upwardly inclined region A of cam 94.

Carried by each supporting ring 103 is a circumferential series of resilient spring metal fingers 120, 120, which fingers are secured at their lower end to said ring by a clamping ring 121. The spring fingers are somewhat tapered toward their free upper ends, and are longitudinally arcuate so as to define a dome-shaped structure 75

rising from the inner circumference of each ring 103. Adjacent their upper ends the fingers 120 are reversely curved as shown and terminate in short, uncurved terminal regions 122 which are 5 disposed parallel to the axis of the ring 103 and head 102 when the fingers 120 are moved a determinate distance radially inwardly. The fingers 120 are of such length that they extend into the lower end portion of the sleeve 104, and when 10 said sleeve is in its uppermost position and the fingers are unrestrained, the terminal portions 122 of the fingers will seat in the enlarged groove or recess 105 in the bore of the sleeve, as shown in the right hand unit of Fig. 7. When the sleeve 15 104 is in its lowermost position, cam surface 106 at the lower end of the sleeve is in engagement with the convex side of fingers 120 so as to flex them toward each other whereby their terminal portions 122 are arranged in a circle of smaller 20 diameter than the opening in a bottle cap, which caps the fingers are adapted to engage as presently will be explained.

As is best shown in Figs. 3 and 7, a tubular magazine 125 is slidably mounted within each 25 tubular sleeve 104, said magazine having a circumferentially extending external flange 126 adjacent its upper end, which flange normally rests upon the upper end of sleeve 104. The lower end of each magazine 125 normally is disposed at the 30 upper margin of groove 105 in sleeve 104, and is formed with a slightly inturned flange or ledge 127 which supports a stack of bottle caps 128, 129. The latter are of the type constituting the subject matter of Gammeter Patent No. 2,157,601 35 aforementioned, and are shown in detail herein in Figs. 3 and 9. As shown in said figures, each cap 128 comprises circular, substantially parallel top and bottom portions 129, 130 respectively, of which the bottom portion has a central opening 40 131 therein. When the sleeve 104 is in lowermost position, the terminal portions 122 of spring fingers 120 extend into the plane of the lowermost caps 128 in magazine 125, so as to engage the lowermost cap and spread the bottom portion 129 45 thereof into a skirt, as subsequently will be explained. The magazines 125 are readily removable from the sleeves 104, and each is formed with a relatively wide slot 132 extending axially from its upper margin to facilitate the insertion 50 of caps into the magazine. The inside diameter of the magazine flange 127 is somewhat smaller than the upper end of a bottle to be capped, the purpose of which arrangement presently will be explained.

As previously stated, lowering of the sleeves 104 moves the fingers 120 radially inwardly, and in their extreme innermost position their terminal portions extend into the plane of the lowermost caps in the magazines 125. It is important that 55 the lowermost caps 128 remain out of engagement with the tips of fingers 120 until the latter have reached their ultimate inner positions since otherwise they would wipe across the lower cap and so crumple it as to make it impossible for the fingers subsequently to grasp it. For this reason means is provided for effecting relative axial movement of each sleeve 104 and its magazine 125 whereby the latter is retained in slightly 60 elevated position until the sleeve is fully lowered. To this end each head 102 is formed with a slot 135 that extends longitudinally from its upper margin, laterally outwardly of one of the slots 109 in the head. Slot 135 is substantially the same length as slots 109, and adjacent its lower 65

end the head is formed with a pair of outwardly projecting ears 136 that are suitably apertured to receive a pivot pin 137. An L-shaped latch member 138 is pivotally mounted at its elbow upon the pin 137, and a torsion spring 139 also 5 mounted upon said pivot pin normally urges the free end of the vertical leg of the latch 138 into the slot 135 and toward a groove 140 in the sleeve 104, said movement being limited by the flange 126 on magazine 125. The groove 140 is substantially coincident with slot 135, and, as is best shown in Figs. 4 and 5, extends from the top of sleeve 104 to a point somewhat below slot 135, said groove being of such depth as to be partly overlain by the flange 126 at the upper end of 10 cap magazine 125. The arrangement is such that when the lever arm 112 lifts the sleeve 104 and with it magazine 125 to elevated position as previously described, the flange 126 of said magazine will be moved to a position above the free end 20 of latch 138, thereby enabling spring 139 to swing said latch on its pivot so that its upper end is in groove 140 below said flange, as shown in Fig. 5. The latch is thereby enabled to support the magazine in elevated position upon descent of 25 the sleeve 104, the latter moving relatively of said magazine.

The latch maintains the magazine 125 in elevated position until the sleeve 104 substantially reaches its fully lowered position and then is 30 withdrawn from engagement with flange 126 to permit the magazine to descend by gravity. For so withdrawing the latch 138, one of the forks of lever arm 112 is formed on its free end with a projecting finger 142 that carries an adjustable 35 contact stud 143, the latter being so positioned as to be in engagement with the horizontally projecting leg of latch 138 when said lever arm is in the extreme sleeve-lowering position. Thus the lever arm 112, by engagement with latch 138, 40 moves the latter out of engagement with the flange 126 of magazine 125 as is clearly shown in Figs. 3 and 4.

As shown in Figs. 3 and 7, shaft 77 extends upwardly beyond cam 117 and is connected at 45 its upper end to a hot air blower indicated as a whole by the numeral 145. The shank 146 of the blower is hollow and communicates with an axial bore 147 in the upper end portion of shaft 77. The bore 147 extends to a point below the 50 position of the capper frame 100 on said shaft, and at its lower end is formed with a single, transversely elongated, lateral port or passage 148, which port periodically and alternately communicates with lateral passages 149, 149 in the 55 sleeve 80 as the latter rotates, said passages 149 being arranged diametrically opposite each other. The position of the port 148 angularly of the shaft 77 bears a definite relation to the angular position of the cam 117 thereon, the port being 60 aligned with the region X of greatest radius of the cam, and being of somewhat greater angular extent than said region X with the result that it discharges air into a passage 149 continuously from a brief interval before a downwardly moving sleeve 104 and magazine 125 reach their lowermost position until a brief interval after said sleeve and magazine start their subsequent rising movement.

Passages 149 communicate with an air distributor housing 151 that is mounted upon the sleeve 80 and secured thereto by set screws 152 so as to rotate therewith. The distributor housing is formed with diametrically opposed vertical bores that constitute sockets in which respective cylin- 70 75

drical valve members 153 are rotatably received, there being ports 150, 150 in the housing providing communication between said sockets and respective passages 149 in the sleeve. Each of the valve members is formed on its lower end with a peripheral flange 154 that overlies the adjacent region of the housing. Each valve member 153 is retained in its socket by means of a cap 155 that is secured to the upper end thereof by means of an axial bolt 156, the cap 155 being of larger outside diameter than the valve member 153 so as to overlie the immediately adjacent housing surface. Relative angular movement of valve member 153 and cap 155 is prevented by a pin 157 that extends through the cap and into the valve structure, said pin projecting somewhat above the cap as shown. As is best shown in Fig. 3, each valve member 153 is formed with an internal cavity 158, which cavity is formed with an inlet port 159 in one side thereof, and an outlet port comprising a hollow radial nozzle 160 in the other side thereof, the port 159 and nozzle 160 being disposed diametrically opposite each other, the delivery end of the nozzle being upwardly directed. Each valve structure 153 is capable of limited angular movement in its socket, the housing 151 being suitably cut away to permit swinging movement of the nozzle 160. Angular movement of a valve structure 153 is adapted to swing its nozzle between two extreme positions, in one of which positions the delivery orifice of the nozzle is below and in axial alignment with a magazine 125, and its port 159 is in registry with port 150 of the housing. In the alternative position of the valve member, nozzle 160 is swung to a point laterally of the magazine 125 and the port 159 of the valve member is out of registry with the port 150 of the housing.

As is best shown in Fig. 6, the cap 155 of each valve structure 153 is formed with two oppositely projecting arms 163, 164 of which the latter constitutes an operating arm. Threaded into the free end of arm 163 is an adjustable laterally projecting stud 165 that engages a boss or abutment 166 formed on the housing 151 when the valve member is swung to the position that carries the nozzle 160 directly below the magazine 125. For swinging the valve member and nozzle to the position mentioned a torsion spring 167 is provided, which spring encircles an axial boss on the cap 155 and has one of its ends in engagement with the upwardly projecting end portion of the pin 157 aforementioned, the other end of said spring bearing against a stud 168 projecting from the lower end of an operating lever 169. The latter is pivotally mounted upon a horizontal axis 170 on the capper frame 100, and has a forked or slotted upper end that straddles a stud 171 carried by a downward extension 172 of the arm 114 of a bell crank aforementioned. The arrangement is such that the lever 169 is operated by the cam 117 through the agency of a bell crank, and concurrently therewith. The lever stud 168 is positioned beside the operating arm 164 of the valve cap 155, and when the bell crank is operated to lift the sleeve 104 and magazine 125, the lever 169 is so moved as to cause stud 168 to engage cap arm 164 and turn the latter and valve 153 counter-clockwise as viewed in Fig. 6, thereby swinging nozzle 160 to a point laterally of its overlying structure, and moving port 159 of the valve out of registry with port 150 of the distributor housing to shut off the flow of air to the nozzle. When the cam 117 causes reverse movement of the lever 169, the stud 168 returns to point of starting and the

torsion spring 167 reverses the movement of the valve member 153, which movement continues until the stud 165 strikes abutment 166. The stud 165 engages abutment 166 before the angular movement of lever 169 ceases, so that stud 168 is in slightly spaced relation to operating arm 164, as shown in the right hand unit in Fig. 6, while the nozzle 160 is under the magazine 125 and discharging air thereinto. This provides a small amount of lost motion between stud 168 and arm 164, with the result that when the cam 117 operates the bell crank to lift sleeve 104, the nozzle continues to discharge air into the magazine until shortly after the sleeve 104 has started to rise and the fingers 120 have started to expand the lowermost bottle cap in the magazine.

In the operation of the machine, it will be assumed that the magazines 125 have been filled with bottle caps 128, that bottles 175 filled with milk or other liquid are ready to be capped, and that the machine has been suitably adjusted to the size of bottles to be capped. The machine being set in motion through the agency of suitable power means provided therefor, the shaft 12 and the sleeve 80 are rotated at uniform speed, 25 the shaft 12 in counter-clockwise direction and the sleeve 80 in clockwise direction, and the conveyor 13 is driven at proper linear speed with relation to the speed of said shaft and sleeve, the upper reach of the conveyor moving toward 30 the right as viewed in Fig. 1. Thus bottles 175 placed upon the conveyor 13 are carried therealong until feed wheel 70 is reached, the leading bottle of the succession of bottles being engaged by one of the cut out portions 74 and conducted 35 thereby to a table 91, the rotation of rotor 86 being so timed that one of the tables 91 will be in proper position to receive the bottle from the feed wheel. Each table 91 is axially aligned with one of the capping heads at all times, so that a bottle 40 deposited on either of the tables 91 will be in position directly beneath one of the capping heads, as is best shown in Fig. 7, ready to be elevated to receive a cap.

The tables 91 and capping heads are continuously moving in clockwise direction, and substantially at the same time a bottle is deposited on a table, the cam roller 93 of the table-supporting post 90 engages the cam track 94 and begins to ride up the steeply inclined portion A 50 thereof. After moving through an arc of 60° the cam roller moves onto the less steeply inclined portion B of the cam track, which track moves the table and bottle thereon to maximum elevation after the table and bottle together have 55 traversed an arc of 180°. The maximum and minimum elevations of a bottle are shown in Fig. 7. At the moment the cam roller 93 first engages cam track 94, cam roller 116 of the capper mechanism directly above the bottle is riding along 60 cam surface Z toward cam surface W of cam 117, with the result that a sleeve 104 and magazine 125 are being lifted, and the nozzle 160 is being swung laterally from beneath the capper head to enable the subsequent admission of a bottle top 65 thereto. The rise of sleeve 104 relieves the annular series of fingers 120 of deforming pressure and they flex outwardly, their terminal ends, which extend through the aperture 131 in the lower ply of the lowermost cap 128, serving to 70 stretch said ply and enlarge the aperture therein. The lowermost cap 128 previously has been warmed by a jet of heated air directed thereagainst, which facilitates the stretching of said lower ply. The condition of the bottle cap at 75

this time is best shown in the left hand unit of Fig. 7.

The sleeve 104 attains its completely elevated position, as shown at the right in Fig. 3, at the 5 time cam roller 116 reaches the end of cam surface Z of cam 117. At this time cam roller 93 is still on cam surface A of cam 94 and the rapidly rising bottle 175 has its upper end approximately within the finger supporting ring 103. Before 10 the top of the bottle engages the fingers 120, the roller 93 moves onto cam surface B of cam 94, so that its rise thereafter is at a slower pace. As the continued rise of the bottle forces its top against the concave side of the group of fingers 120, said 15 fingers are forced radially outwardly against the confining tension of the bottle cap 128 thereon, and further stretch the aperture 131 thereof so that the bead at the top of the bottle may enter the same, this operation occurring before the 20 bottle is fully elevated and being shown most clearly at the right in Fig. 3. As the bottle still continues to rise it strips the cap 128 from the terminal ends of the fingers 120, and the latter, relieved of the confining tension of the cap, spring 25 outwardly and are received in the groove 105 in the lower end of sleeve 104, as shown at the right in Fig. 7. Still rising, the fully capped bottle strikes the inturned flange 127 at the lower end of magazine 125, and lifts said magazine 30 relatively of the sleeve 104, as shown in Fig. 7, the flange 126 at the upper end of the magazine being thereby elevated above the free end of latch 138, with the result that spring 139 forces said 35 latch into groove 140 of sleeve 104, below said flange, as shown in Fig. 5. This is the condition that obtains when the cam roller 93 is at the end or highest point of cam surface B of cam 94, and the bottle has been conveyed through an arc of 180°.

40 As the rotor 86 continues to revolve, cam roller 93 moves onto downwardly inclined cam surface C of cam 94, and the capped bottle starts its descent, the capped upper end readily withdrawing through the widely spread fingers 120. 45 Descent of the bottle lowers the magazine 125 until its flange comes to rest upon the upper end of sleeve 104, somewhat above the upper end of latch 138. The bottle attains fully lowered position as the cam roller 93 passes off the end of cam 50 surface C of cam 94, the descent being relatively quickly accomplished. Continued rotation of the rotor 86 brings the capped bottle around to a point adjacent the inner end of guard rail 54 by which it will be swept off its table 91 and deposited 55 upon stationary table 48 to be gathered up for distribution in the usual manner.

While bottle 175 is about midway of the descending movement just described, cam roller 116 starts the traverse of cam surface Y of cam 117, 60 with the result that sleeve 104 and magazine 125 start to move downwardly and spring 167 starts to swing nozzle 160 to position beneath the capping head, the bottle at this time being lowered sufficiently to allow the swinging movement of 65 the nozzle. Descent of the magazine 125 continues until its flange 126 comes to rest upon the upper end of latch 138, which is about one-half inch above fully lowered position. Swinging movement of the nozzle 160 continues until the 70 stud 165 of valve arm 163 strikes abutment 166, in which position of the nozzle the valve 153 is open and heated air is discharged from the nozzle to impinge upon the lowermost cap 128 in magazine 125. The effect of the heated air is to soften 75 the material of the cap and to separate the lower

ply thereof from the upper ply. The nozzle 160 reaches operative position before the sleeve 104 is fully lowered so that the lever arm 169 moves out of engagement with the operating arm 164 of the valve cap 155. As the sleeve 104 descends its 5 lower marginal cam 106 engages the fingers 120 and flexes them radially inwardly so that their terminal portions 122 are arranged in a circle of smaller diameter than the aperture 131 in a cap 128. Immediately before the sleeve 104 is fully 10 lowered, the stud 143 carried by arm 112 strikes the horizontal portion of latch 138 and withdraws the upper end thereof from beneath flange 126 of magazine 125, permitting the latter to drop until said flange engages the upper end of sleeve 15 104. This causes the lowermost cap 128 in the magazine to be engaged by the fingers 120, with the terminal portion of the fingers within the aperture 131 of the cap as is clearly shown at the left in Fig. 3.

The sleeve 104 becomes fully lowered when the cam roller 116 reaches cam surface X of cam 117, and retains this position while the roller traverses said cam. As soon as cam roller 116 moves onto cam surface Z of cam 117, the sleeve 104 starts its 25 rising movement whereby the fingers 120 stretch the bottle cap 128 as previously explained. Because of the lost motion between the stud 168 of lever 169 and the operating arm 164 of valve cap 155, the nozzle 160 is not swung laterally from 30 under the capper head until after the fingers 120 start to stretch the bottle cap, thereby assuring that the heated air from the nozzle will impart optimum elasticity to the cap. The cam roller 116 is still on cam surface Z of cam 117 when the 35 rotation of the capper frame and rotor bring the various mechanisms of the apparatus to the point of starting, thereby completing a cycle of operation.

Since the apparatus is a duplex machine, it will 40 be understood that the cycle of operations described with relation to one bottle will be performed concurrently upon another bottle in the machine. However, the invention is not limited to a duplex machine, and the apparatus may be 45 so constructed as to accommodate either one or a plurality of bottles at a time. The operation of the machine is continuous and automatic; it is simpler than the machine of my prior patent aforementioned, and it achieves the several 50 objects set forth in the foregoing statement of objects.

Modification may be resorted to without departing from the spirit of the invention, or the scope thereof as defined by the appended claims. 55

What is claimed is:

1. A bottle capping machine comprising, in combination, means for supporting in stack formation a plurality of flexible caps each having a substantially flat top portion and a substantially 60 parallel bottom portion having an axial opening therein, a circular series of flexible fingers in axial alignment with said stack operable to engage the bottom portion of the lowermost cap in said stack and to form said bottom portion into 65 a skirt and to enlarge the opening in said bottom portion to a size sufficient to admit the head of a bottle, means for effecting relative axial movement of the stack and said series of fingers, and means for flexing said fingers in determinate time 70 relation to said relative axial movement.

2. A bottle capping machine comprising, in combination, a magazine supporting a plurality of flexible caps in stack formation, a supporting structure for said magazine capable of axial 75

movement relatively thereof, a circular series of flexible fingers in axial alignment with said stack and operable to expand and hold expanded at least a portion of the lowermost cap of the stack, 5 means for effecting relative axial movement of the magazine supporting structure and said series of fingers, and means for flexing said fingers in determinate time relation to said relative axial movement.

10 3. A bottle capping machine comprising, in combination, a magazine carrying a plurality of flexible caps in stack formation, a supporting structure for said magazine capable of axial movement relatively thereof, a circular series of 15 flexible fingers in axial alignment with said stack and operable to expand and hold expanded at least a portion of the lowermost cap of the stack, means for effecting relative axial movement of the magazine supporting structure and said series 20 of fingers, means for effecting relative axial movement between the magazine and its supporting structure, means for effecting relative axial movement between the said supporting structure and said series of fingers, and means 25 for flexing said fingers in determinate time relation to said axial movement of the magazine supporting structure.

4. A bottle capping machine comprising, in combination, a magazine supporting a plurality of 30 flexible caps in stack formation, a supporting structure for said magazine, a circular series of flexible fingers in axial alignment with said stack and operable to expand and hold expanded at least a portion of the lowermost cap of the stack, 35 said magazine supporting structure being in physical contact with said fingers, and means for moving said magazine supporting structure axially relatively of the series of fingers to effect a radial flexure of said fingers.

40 5. A bottle capping machine comprising the combination of a magazine for supporting a plurality of flexible caps in stack formation, a supporting structure for said magazine capable of axial movement relatively thereof, a circular series 45 of flexible fingers in axial alignment with said stack and operable to expand and hold expanded at least a portion of the lowermost cap of the stack, said magazine supporting structure being in physical contact with said fingers, means 50 for moving said magazine supporting structure axially relatively of the series of fingers to effect radial flexure of said fingers, and means for effecting relative axial movement between the magazine and its supporting structure in determinate time relation to the flexing of said fingers.

6. A bottle capping machine comprising the combination of a capper frame, a circular series 55 of arcuate flexible fingers carried by said frame, an axially movable sleeve carried by said frame in axial alignment with said series of fingers, above the latter and in physical contact with the fingers, means for moving the sleeve axially relatively of the series of fingers to flex the latter in a radial direction, and a magazine for bottle caps 60 in said sleeve, said magazine being so positioned that the free ends of the fingers extend into the plane of the lowermost cap at least in said magazine in one axial position of the sleeve.

7. A bottle capping machine comprising the combination of a capper frame, a circular series 65 of arcuate flexible fingers carried by said frame in fixed position thereon, an axially movable sleeve carried by said frame in axial alignment with said series of fingers, above the latter and 70 in physical contact therewith, a magazine for

bottle caps in said sleeve and movable axially relatively thereof, said magazine having one position in which the free ends of the fingers extend into the plane of the lowermost cap at least in said magazine, means for moving the sleeve 5 relatively of the series of fingers to effect flexing movement of the fingers in a radial direction, and means for moving the magazine relatively of the sleeve in determinate time relation to said axial movement of the sleeve.

10 8. A bottle capping machine comprising the combination of an annular series of arcuate flexible fingers defining a dome-shaped structure with the free ends of the fingers arranged in a circle in the middle thereof, a tubular sleeve in 15 axial alignment with said series of fingers on the convex side thereof, the free ends of the fingers extending into the sleeve and the lower margin of the latter engaging said fingers, means for raising and lowering the sleeve to effect flexure of the fingers whereby the free ends thereof are moved radially, and a magazine for bottle caps in said sleeve, the free ends of the fingers extending into the plane of the lowermost cap at least, in said magazine, in the lowered position 25 of the sleeve.

9. A combination as defined in claim 8 in which the magazine is slidably mounted in the sleeve, including means for effecting axial movement of the magazine relatively of the sleeve.

30 10. A bottle capping machine comprising the combination of an annular series of arcuate flexible fingers, a tubular sleeve in axial alignment with said series of fingers, above the same and in physical contact therewith, means for raising 35 and lowering the sleeve to effect radial movement of the free ends of the fingers, a magazine for a stack of bottle caps mounted for sliding movement in said sleeve, and latch means engageable with said magazine to retain it in an 40 elevated position within said sleeve.

11. A bottle capping machine comprising the combination of an annular series of arcuate flexible fingers, a tubular sleeve disposed axially thereof with its lower margin in physical contact 45 with said fingers, a magazine for a stack of bottle caps mounted within the sleeve for relative movement axially thereof, latch means engageable with said magazine to retain the latter in elevated position within the sleeve, means for 50 raising and lowering the sleeve to effect operation of the flexible fingers, and means for releasing said latch in determinate time relation to the axial movement of the sleeve, thereby enabling the magazine to descend by gravity.

55 12. A bottle capping machine comprising the combination of an annular series of arcuate flexible fingers, a tubular sleeve disposed coaxially therewith with its lower margin in physical contact with said fingers, a magazine for a stack of 60 bottle caps mounted within the sleeve and capable of relative movement axially thereof, latch means engageable with said magazine to retain the latter in elevated position within the sleeve, a lever arm engaging said sleeve for raising and 65 lowering the same to effect flexing of the fingers, and means on the lever arm engageable with said latch to operate the same to release the magazine when said lever arm has moved the sleeve to determinate position, said magazine thereafter 70 descending by gravity.

75 13. A bottle capping machine comprising the combination of an annular series of flexible fingers, a tubular sleeve disposed coaxially therewith with its lower margin in physical contact

with said fingers, a magazine for a stack of bottle caps mounted within said sleeve, a swingable hot air delivery nozzle disposed below the fingers and movable between axial alignment therewith 5 and a position laterally thereof, and means for concurrently moving said sleeve axially and said nozzle angularly, said means comprising a cam and interconnected lever means operated thereby.

14. A bottle capping machine comprising the 10 combination of an annular series of flexible fingers, a tubular sleeve disposed coaxially therewith with its lower margin in physical contact with said fingers, a magazine for a stack of bottle caps carried within said sleeve, a swingable hot 15 air delivery nozzle disposed below the fingers and movable between axial alignment therewith and a position laterally thereof, lever means for concurrently moving said sleeve axially and said nozzle angularly in one direction, and yielding 20 means for moving said nozzle angularly in the opposite direction.

15. A combination as defined in claim 14 including a lost motion connection between the nozzle structure and the lever means which delays 25 the angular movement of the nozzle toward its lateral position until after said lever means has started to elevate the sleeve.

16. A bottle capping machine for applying flexible caps to bottles, each cap having a flat top 30 portion and a substantially parallel bottom portion having an axial opening therein, said machine comprising a plurality of arcuate flexible fingers in circular arrangement defining a dome-shaped structure, the fingers being fixed at the 35 large end of the dome, the free ends of the fin-

gers being reversely curved and having straight terminal portions that are disposed in a circle of smaller size than the axial opening in a cap when the fingers are flexed toward each other, and an annular cam structure embracing said fingers 5 and axially movable relatively thereof into operative engagement with the arcuate portions thereof for flexing said fingers.

17. A bottle capping machine for applying flexible caps to bottles, each cap having a flat top 10 portion and a substantially parallel bottom portion having an axial opening therein, said machine comprising a circular series of arcuate flexible fingers defining a dome-shaped structure, the fingers being fixed at the large end of the dome, 15 the free ends of the fingers having straight terminal portions that are disposed in a circle on the convex side of the small end of the dome when the fingers are flexed toward each other, said terminal portions of the fingers being insertable in the axial aperture of a cap, the stiffness of the fingers being such that when they are relieved of flexing pressure they stretch said aperture and bottom portion of the cap nearly to a size sufficient to admit the end of a bottle to 20 be capped, an annular cam structure surrounding said fingers, and means for moving said cam structure axially of said fingers a determinate distance between the respective ends of said fingers whereby said cam in one position engages and 25 flexes said fingers and in another position limits the radially outward movement of the fingers after the cap has been removed from the ends thereof.

LYNN L. SEYMOUR. 35
